Attorney

UNITED STATES PATENT OFFICE

EDWARD STINDL, OF BELOIT, WISCONSIN

STEPLADDER EXTENSION

Application filed July 11, 1928, Serial No. 291,814. Renewed June 27, 1932.

The present invention relates to improvements in step ladders and has reference more particularly to an extension for the side bars or uprights of the front and rear sections of a conventional step ladder, whereby the height of the ladder may be increased, in order to reach parts that are ordinarily inaccessible when standing upon a conventional step ladder.

10 Another important object of the invention is to provide a step ladder extension that can be readily and easily attached or detached, means being provided for positively securing the extension on the lower ends of the side bars or uprights of the front and rear sections of the ladder, so that there will be no danger of a person injuring himself while using the step ladder with the extension attached thereto.

20 A further object is to provide a step ladder extension which is simple in construction, inexpensive, strong and durable, and further well adapted to the purpose for which it is designed.

25 Other objects of the invention will become apparent as the nature of the invention proceeds and when taken in connection with the accompanying drawings, forming a part of this application and in which drawings:

30 Figure 1 is a side elevation of a conventional step ladder, showing my improved extension attached thereto.

Figure 2 is a fragmentary front elevation thereof.

35 Figure 3 is a fragmentary rear elevation thereof.

40 Figure 4 is a detail perspective view of the upper end portion of one of the side bars or uprights of the front unit of the extension, showing the clamping members secured thereon for receiving the lower end portion of the adjacent side bar of the front section of the step ladder.

45 Figure 5 is a detail showing the manner in which the lower end of one of the side bars of the front section of the conventional step ladder fits in the socket provided therefor on the adjacent side bar or upright of the front extension unit, the lower end of the side bar or upright of the step ladder resting on the

uppermost step of the front unit of the extension.

Figure 6 is a detail plan view of the U-shaped clamping member, showing the manner in which the same embraces the side bars 55 of the step ladder and its extension, and

Figure 7 is a detail of a modification of the clamping means.

In the drawings, for the purpose of illustration is shown a step ladder of the conventional construction, the same comprising the front and rear sections 2 and 3 respectively. The front section of the step ladder includes the conventional side bars or uprights 4 that are disposed at an incline and extending between the spaced side bars of the front section are the vertically spaced steps 5. A platform 6 is secured on the upper ends of the side bars or standards 4.

The rear section 3 includes the side bars 7 that are connected together by the usual bracing members 8 and the upper ends of the side bars 7 are pivotally secured to plates fixed to the front uprights. Hinged-75 connected braces 9 extend between the respective side bars or uprights of the front and rear sections in the manner also well known in the art.

My improved step ladder extension includes the front and rear units 10 and 11 80 respectively. The front unit includes a pair of side bars or uprights 12, which are interconnected by means of the steps 13 and the lower ends of these side bars are cut away at an angle so that when the front unit 10 85 is positioned with respect to the side bars of a front section 10 of the step ladder 1, the side bars of the front unit will be in alignment with the respective side bars of the step ladder as clearly indicated in Figure 1. Furthermore, the steps 13 are of such length as to cause the side bars or uprights 12 to be disposed against the outer faces of the lower end portions of the side bars or standards 4 of the front section 2 as clearly indicated in Figure 2.

90 A rectangular shaped socket member 14 is attached to each side bar 12 of the front extension unit 10, directly above the uppermost step of the front extension unit, and this 100

socket member is formed by taking a strip of metal and bending the same in the manner as shown in Figure 4, so that the socket will be disposed on the inner side of the respective side bar 12.

These socket members are rigidly secured to the side bars of the front extension unit 10 and the lower ends of the respective side bars 4 of the front section 2 of the step ladder 10 are receivable in these socket members so that the lower ends of said side bars 4 will rest upon the uppermost step of the unit 10, as suggested very clearly in Figure 5.

A substantially U-shaped clamp is carried by the uppermost end of each side bar 12 of the front unit 10 and this U-shaped clamp 15 has one of its arms 16 fixedly secured to the outer face of the side bar 12 and the crown portion 17 of this U-shaped clamp extends across the forward edge of the side bar. In this manner, the other arm 18 of the U-shaped clamp is spaced from the inner face of the side bar 12 for accommodating the adjacent portion of the respective side bar 4 of the front section 2 of the step ladder 1, as clearly shown in Figure 6.

Each of the U-shaped clamps 15 is disposed at right angles with respect to the upper end of each side bar of the extension unit 10 and the arms 16 and 18 are of such length as to project beyond the rear edges of the abutting side bars 4 and 12. A projecting end of the arms are slightly bent outwardly and the outer end of the arm 16 is formed with an opening 19 while the outer end of the other arm 18 of each clamp 15 is formed with an inwardly extending slot 20.

A bolt 21 extends through the opening 19 and through the slot 20, the head of the bolt engaging with the outer face of the apertured end of the arm 16 while a thumb nut 22 is threaded on the threaded end of the bolt that projects beyond the outer side of the slotted outer end of the arm 18 and manifestly by turning the thumb nut in one direction, the U-shaped clamp 15 will be drawn tightly against the adjacent portion of the respective side bar of the front section of the step ladder, so that a rigid connection will be provided between the front extension unit 10 and the front section of the step ladder.

The rear extension unit 10 includes the spaced side bars or uprights 23 that are connected together by appropriate bracing means 24, and these side bars are of substantially the same size as the side bars 7 of the rear section 3 of the step ladder 1 and the ends of the side bars 23 are cut at an angle as indicated in Figure 1. A socket member 25 similar to the socket member 14 is secured on each of the uprights or side bars 23 at a point downwardly of the upper end thereof for receiving the lower end of the respective side bar 7 of the rear section 3 and a block 26 may be secured on the inner side of each upright or side

bar 23, for cooperation with the respective socket 25 to provide a rest for the lower end of the respective side bar of the rear section of the step ladder as shown very clearly in Figure 3.

A substantially U-shaped clamp, designated generally by the numeral 27 and similar to the clamp 15 is carried by the upper end of each upright or side bar 23 of the rear extension unit 11, for cooperation with the adjacent portion of the respective upright or side bar of the rear section of the step ladder, and a bolt and nut connection is provided for the free ends of the arms of each U-shaped clamp 27 for the same purpose as the bolt and nut connection associated with each of the U-shaped clamps 15 and this bolt and nut connection that is associated with each of the clamps 27 is shown generally at 28.

When the parts are arranged as shown in Figures 1, 2, and 3, it will be readily apparent that the step ladder 1 may be used to reach places that would ordinarily be inaccessible without the extension units 10 and 11, and due to the simplicity of construction, the extension units can be readily and easily attached or disengaged from the respective uprights or side bars of the front and rear sections of the step ladders. It is also to be understood that the extension unit may be of different heights, so that the height of the step ladder may be increased as is desired.

In Figure 7 of the drawings, there is shown a modification of the clamping means associated with the upper end of each of the side bars of the extension unit.

This particular clamp comprises a U-shaped member that has one arm 29 secured to the upper end of the side bar of each extension unit, the other arm of this U-shaped clamp having its free end disposed laterally as at 30, while the free end of the arm 29 is constructed to form a notched keeper 31, for receiving the hook 32, that is formed on the outer end of a lever 33, which lever is pivoted at its inner end on the laterally disposed portion 30, as at 34. A handle forming portion 35 is provided on the outer extremity of the lever 33, to facilitate the disengagement of the hook 32 from its keeper 31 when it is desired to disengage the adjacent side bar 12 or the side bar 7 from the side bar 23.

It will also be observed that the side bar 12 of the front extension unit 10 is cut out as at 36 to receive the head of the bolt that supports the adjacent step of the front section of the step ladder.

While I have shown the preferred embodiment of my invention, it is to be understood that various changes in the size, shape and arrangement of parts may be resorted to, without departing from the spirit of the invention or the scope of the appended claim.

What I claim is:

In a ladder construction, a main ladder sec-

tion, an extension section, a socket forming member carried by each side member of the extension section for receiving the lower end of each side member of the main ladder section, a U-shaped member having one of its limbs connected to the upper end of each side member of the extension section with its bight extending across and to a considerable distance beyond an end edge of said side member, whereby the other limb of the U-shaped member is spaced from the opposite side of the said side member for receiving a side member of the main section, the ends of the limbs projecting beyond the side members and detachable means for connecting the ends of the limbs together.

In testimony whereof I affix my signature.
EDWARD STINDL.
